(57) **CLAIM**

The ornamental design for a blood glucose test meter, as shown and described.

DESCRIPTION

FIG. 1 is a front elevational view of the blood glucose test meter;

FIG. 2 is a rear elevational view of the blood glucose test meter;

FIG. 3 is a left side elevational view of the blood glucose test meter;

FIG. 4 is a right side elevational view of the blood glucose test meter;

FIG. 5 is a top plan view of the blood glucose test meter;

FIG. 6 is a bottom plan view of the blood glucose test meter; FIG. 7 is a perspective view of the blood glucose test meter; and,

FIG. 8 is another perspective view of the blood glucose test meter.

The broken lines in the drawing views are included for the purpose of illustrating portions of the blood glucose test meter that form no part of the claimed design.
